AEROSOL VALVE DEVICE

Roger Remané, Sainte-Colombe-les-Vienne, France, assignor, by mesne assignments, to Airkem, Inc., New York, N.Y., a corporation of New York

Filed July 5, 1961, Ser. No. 122,021

Claims priority, application France July 29, 1960
8 Claims. (Cl. 239—573)

This invention relates to improvements in aerosol valves, i.e., valves for atomizing containers intended to eject as a fine spray or aerosol products in suspension or in solution in a liquified gas under pressure which acts as a propelling agent. More particularly, the invention relates to an aerosol valve comprising an assemblage of rigid and movable valve parts forming a container closure, permitting rapid pressure filling of propelling agent and having detachably secured to the movable valve part a two-piece cap forming push-button and flow control means for actuating said valve.

In the use and operation of aerosol valves, it is important on the one hand to provide a small, accurately controlled discharge, to avoid useless or too rapid consumption of product as the valve is actuated, and on the other hand to provide for rapid filling of containers with the desired amount of liquified gas. According to one process in use at the present time, a container is filled with the liquified gas before attachment of the valve thereto by conducting the filling operation at a reduced temperature ranging from -20° C. to -30° C., which strongly reduces the vapor pressure of the liquified gas, and attaching or setting the valve to the container opening, while still at the reduced temperature. This process, which is known as cold filling, permits rapid filling of containers, even though valves may be designed with very restricted passages to provide a suitable discharge, but the need for operating at sufficiently low temperatures to maintain the gas liquified makes the process very expensive.

According to another process known as pressure filling, the valve, with the control cap or push-button removed, is first attached to the container, and then through a pipe which envelops the valve and engages the container liquified gas under pressure is forced through the valve into the container. While this process avoids the need for external cooling and is thus less expensive than the cold fill process, it is nevertheless difficult to obtain valves which will permit rapid flow during filling, enabling this operation to be completed in a short time, and will also provide a sufficiently small delivery when using the valve to produce an aerosol spray. None of the known valves fully satisfies these conditions, despite most elaborate embodiments which practically amount to the manufacture of double valves with different cross-sectional areas for filling and discharge.

The valve according to the present invention overcomes the problems above mentioned in a simple and practical way and is characterized in that it is designed to ensure, when open with push-button cap removed, a flowing area sufficient to permit fast filling with propelling agent, and further characterized in that a removable push-button cap containing an atomizing port is provided with a calibrated passage, corresponding to the required delivery when in use, between the inside of the cap and the atomizing port. Thus, the new valve offers a large opening, sufficient for fast filling, while the delivery is limited when in use by the push-button cap which is attached to the valve after filling.

By way of example, two forms of embodiments of the invention are described hereafter and illustrated in axial section in FIG. 1 and FIG. 2 of the accompanying drawing as applied to a valve of a known type, in which a stationary valve member cooperates with a seat provided on

2

an elastically distortable diaphragm which secures the closing by action upon said diaphragm of the pressure existing in the container.

FIG. 1 is an axial sectional view of an entire valve assembly according to the present invention, and FIG. 2 is a similar sectional view of the top portion of the valve assembly of FIG. 1 showing a modification in the cap construction.

As illustrated in FIG. 1, a container opening 1 is provided with a shoulder 2 inwardly spaced from the edge 3 of the container opening, upon which a valve assembly "a" is set or clamped by folding in of the edge 3, as shown. The valve assembly "a" includes a substantially flat rigid base member 4, having a downward tubular extension 5 to receive a conventional dip-tube, and a flexible, or elastically deformable diaphragm 6 having a central upward tubular extension 7 providing an annular valve seat 8 outwardly of said diaphragm. The base member 4 and diaphragm 6 are secured together by a valve member 9, having an enlarged head 10 engaging the valve seat 8, and an elongated stem 11 terminating in formed end 12 providing snap lock engagement with a tapered aperture 12 centrally of the base 4.

The diameter of the stem 11 is substantially smaller than the internal diameter of the tubular extension 7, providing an annular passage 14 therebetween communicating with the chamber 15 between the base and diaphragm for rapid flow of fluid when the valve seat 8 is separated from the valve head 10. Within the dip-tube extension 5, the base member is provided with fluid passage means 16, two being shown in the drawing, also communicating with the chamber 15 between the base and diaphragm, thus completing the path of flow of fluid through the valve assembly "a".

Certain details of the interengaging structure of the base 4 and diaphragm 6 as shown in the drawing are of particular significance in providing assemblage to a container which will be fluid tight in all conditions encountered in pressure filling, storage and use. It will be noted that the base member 4 has an annular ribbed periphery 17 for downward bearing engagement with the shoulder 2 of a container, and the diaphragm 6 has an annular peripheral rib 18 in alignment with the rib 17 and around which the container edge 3 can be folded. Inwardly spaced from the rib 18, the diaphragm 6 has a shallow cylindrical wall 19 extending downwardly from the central thin walled portion 20, the inner surface of said cylindrical extension 19 slidably engaging the outer surface of an upwardly extending annular rib 21 on the base member. As the assembly "a" is clamped in a container opening between the shoulder 2 and inturned edge 3, the compression on the ribs 17, 18 and resulting lateral pressure of the wall 19 against the rib 21 provides a most effective seal between the base member and diaphragm. The seal can be further enhanced, if desired, by providing on opposed faces of the base and diaphragm small interfitting annular rib and groove means, as indicated at 22.

A significant factor is the small volume of the chamber 15 provided by the interfitting structure, as above described. At the same time, the chamber 15 is of sufficient depth to permit full unseating of the valve head 10 as the central portion of the diaphragm is depressed.

The push-button cap assembly or discharge means 23 is a two part structure comprising an essentially tubular or hollow sleeve 24, having a lower bore 25 slidably engaging the outer surface of the tubular diaphragm extension 7, and a larger diameter upper bore 26 receiving a plug 27, which closes the upper end of the cap assembly. The lower end of the body 24 has an annular, downwardly extending flange 28 adjacent the bore 25 for direct bearing engagement with the central portion 20 of the diaphragm to downwardly flex the diaphragm as axial

pressure is applied to the push-button assemblage 23. The lower end of the body 24 also includes a flexible, laterally extending skirt 29 terminating in an annular, downwardly extending peripheral flange 30, which is disposed loosely between the cylindrical extension 19 of the diaphragm and the inturned edge 3 of the container. The skirt thus overlies and protects upper surfaces of the diaphragm.

The upper portion of the body 24 has a lateral passage or atomizing port 31 communicating with an enlarged diameter portion 32 of the upper bore 26. The plug 27 is of stepped cylindrical construction, having a lower end portion 33 extending throughout a major portion of its length and having a diameter to closely engage the bore 26, an intermediate portion 34 having a diameter to closely engage the bore 32, and an enlarged top flange 35 interfitting with an annular recess 36 for positioning and retaining the plug 27 in the tubular body 24. The elongated lower end 33 of the plug 27 extends a substantial distance into the enlarged diameter portion 32 to form an annular groove or expansion chamber 37 in alignment with the atomizing part 31.

At the engaged surfaces of the lower end 33 of the plug and the bore 26 of the tubular body, calibrated passage means is provided to establish communication between the expansion chamber 37 and the chamber 38 formed between the valve assemblage "a" and the push-button assemblage 23. As shown in FIG. 1 of the drawing, this passage is formed by a groove 39 in the plug 27, whereas, in the modification shown in FIG. 2, this passage is formed by a groove 40 in the tubular body 24. It will be apparent that, with either form of construction, the parts can be readily molded, preferably from plastic material. Also, the calibrated passage provided by the groove 39 or the groove 40 can be modified in cross-sectional area, and resulting flow capacity, to properly control the discharge rate for different aerosol products to be dispensed. The modification shown in FIG. 1 is considered preferable since with the construction the assemblage "a" and the tubular body 24 can be the same for all valves and plugs 27 with the appropriate sized passage or groove 39 can be inserted according to the requirements of the aerosol product to be dispensed.

The lower face 41 of the plug 27 is sufficiently spaced from the valve head 10 to permit downward flexure on the central portion 20 of the diaphragm and unseating of the valve seat 8 as downward finger pressure is applied to the push-button assemblage 23. As long as the push-button assemblage is depressed, there will be a flow of container contents through the passages 16, chamber 15, passage 14, chamber 38, passage 39 (or 40), and chamber 37 with final discharge through the atomizing port 31. When finger pressure is released, the internal pressure in chamber 15 acting against the central portion 20 of the diaphragm re-engages the valve seat 8 and valve head 10 to stop the discharge of container contents.

When the new valve is to be employed in the preferred pressure filling technique, the valve assemblage "a" is attached to a container, prefilled with the desired quantity of product to be dispensed, by placing the assemblage "a" in the container opening and turning over the edge 3 to clamp and seal the ribs 17, 18 against the shoulder 2. The top of the container is then engaged by a pipe feeding propellant gas under pressure and the pressure of the gas brings about a downward distortion of the central portion 20 of the diaphragm and a sufficient separation of the valve seat 8 from the valve head 9 to permit fast filling of the container with propellant gas. After filling with propellant, the push-button assemblage 23, with the appropriate size passage 39 (or 40) for the particular product, is slid over the tubular extension 7 of the diaphragm and the aerosol package is complete and ready for use.

I claim:

1. An aerosol valve device comprising a substantially flat rigid base member having an annular downwardly ribbed periphery adapted for downward bearing engagement with annular bearing means of a container part, a flexible diaphragm having an annular ribbed periphery adapted for fluid-tight bearing engagement with the periphery of said base member, thereby forming between said diaphragm and base member a fluid chamber, said base member having an aperture permitting communication between said fluid chamber and the interior of an associated container, said diaphragm having a center opening providing an annular valve seat outwardly of said diaphragm, a valve member having an enlarged portion registering with said valve seat and an elongated stem extending through said fluid chamber and interlocked with retaining means on said base member, the tension of said flexible diaphragm acting to normally support said valve seat in engagement with said valve member while permitting the disengagement of said valve member and seat in the downward flexing of said diaphragm, and the central portion of said flexible diaphragm being closely spaced from said base member whereby said fluid chamber is shallow and of limited fluid capacity.

2. An aerosol valve device as defined in claim 1 where-
in the base member has on the upper surface thereof an annular, upwardly extending rib providing a vertical outer circumferential surface for slidably interfitting with a vertical inner circumferential surface on said flexible dia-
phragm.

3. An aerosol valve device as defined in claim 1 where-
in said flexible diaphragm includes a main central por-
tion of essentially circular thin walled structure joining
at its outer edge a thin walled shallow cylindrical down-
ward extension, the inner surface of said cylindrical ex-
tension slidably engaging the outer surface of an upwardly
protruding annular rib on said base member.

4. An aerosol valve device as defined in claim 1 where-
in said flexible diaphragm includes a main central por-
tion of essentially circular thin walled structure joining
at its outer edge a thin walled shallow cylindrical down-
ward extension, the inner surface of said cylindrical ex-
tension slidably engaging the outer surface of an upwardly
protruding annular rib on said base member, and said flexi-
ble diaphragm having outwardly of said cylindrical exten-
sion and radially spaced therefrom an upwardly extending
annular rib, the outer circumferential surface of said rib
being in common alignment with the downwardly ribbed
periphery of said base member.

5. An aerosol valve device as defined in claim 1 where-
in said flexible diaphragm includes a main central por-
tion of essentially circular thin walled structure joining
at its outer edge a thin walled shallow cylindrical down-
ward extension, the inner surface of said cylindrical ex-
tension slidably engaging the outer surface of an upwardly
protruding annular rib on said base member, said valve
seat being in a hub part protruding upwardly from said
central portion of the diaphragm, discharge means for
said valve having slidable engagement with the outer sur-
face of said hub part, said discharge means including a
flexible skirt overlying and protecting the central portion
of said diaphragm, the major portion of said skirt being
spaced from said flexible diaphragm by downwardly pro-
truding means having annular bearing engagement with
said diaphragm adjacent the hub part thereof.

6. A detachable cap for atomizing valves comprising two
interfitting parts, one of said parts being an essentially
tubular sleeve having means at one end for telescopic
engagement with an atomizing valve, the other of said parts
being an essentially cylindrical plug telescopically fitting
within the other end of said sleeve, said plug having a
shallow top section of maximum diameter, an intermediate
section of substantially reduced diameter and a bottom
section having a diameter slightly less than said interme-
diate section with the length of said bottom section being

greater than the length of said intermediate section, said sleeve having an outer bore, an intermediate bore, and an inner bore for closely receiving respectively the top, intermediate and bottom sections of said plug, the intermediate bore of said sleeve being of approximately the same length as the bottom section of said plug whereby in assembled position there is formed an annular chamber between said sleeve and plug, a radial discharge orifice within said sleeve in alignment with said annular chamber, and means forming a fluid passage between the 10 bottom section of said plug and inner bore of said sleeve communicating with said annular chamber.

7. A detachable cap for atomizing valves as defined in claim 6 wherein said last named passage is formed by groove means in said plug.

8. A detachable cap for atomizing valves as defined in claim 7 wherein said last named passage is formed by groove means in said sleeve.
